INCANDESCENT LUMINAIRE REFRCTOR

Yearl S. Wince, Newark, Ohio, assignor to Holophane Company, Inc., New York, N.Y., a corporation of Delaware

Continuation of design application Ser. No. 74,686, Apr. 30, 1963. This application Jan. 22, 1965, Ser. No. 83,525

Term of patent 14 years

(Cl. D48—16)

FIG. 1 is a perspective view of an incandescent luminaire refractor embodying the invention;

FIG. 2 is a fragmentary bottom view thereof;

FIG. 3 is an enlarged fragmentary elevational view of one of the corners of the refractor shown in FIG. 1.

This is a continuation of design application Serial No. D.74,686, filed April 30, 1963 and now abandoned.

What I claim is:

The ornamental design for an incandescent luminaire refractor, substantially as shown and described.
